(57) **CLAIM**

The ornamental design for a reciprocating gas compressor valve, as shown and described.

DESCRIPTION

FIG. 1 is an overall perspective view of a reciprocating gas compressor valve showing our new design; FIG. 2 is an overall exploded perspective view thereof; FIG. 3 is an overall top view thereof; FIG. 4 is an overall side elevational view thereof; FIG. 5 is an overall bottom view thereof; FIG. 6 is a cross-sectional view of the reciprocating gas compressor valve of FIG. 3; FIG. 7 is a top view of the seat of the reciprocating gas compressor valve of FIG. 1; FIG. 8 is a side elevational view of the seat thereof; FIG. 9 is a bottom view of the seat thereof; FIG. 10 is a perspective view of the cartridge of the reciprocating gas compressor valve of FIG. 1; FIG. 11 is a bottom perspective view of the cartridge thereof; FIG. 12 is a top view of the cartridge thereof; FIG. 13 is a bottom view of the cartridge thereof; FIG. 14 is a side view of the cartridge thereof; FIG. 15 is a top view of the sealing element that can be used in the reciprocating gas compressor valve of FIG. 1; FIG. 16 is a side view of the embodiment of the sealing element thereof; FIG. 17 is a bottom view of the embodiment of the sealing element thereof; FIG. 18 is a perspective view of the cartridge of the reciprocating gas compressor valve of FIG. 1 showing the sealing element; FIG. 19 is a bottom perspective view thereof; FIG. 20 is a top view thereof; FIG. 21 is a bottom view thereof; FIG. 22 is a side view thereof; FIG. 23 is an overall top view of the guard of the reciprocating gas compressor valve of FIG. 1; FIG. 24 is a side elevational view of the guard thereof; and, FIG. 25 is a bottom view of the guard thereof. The broken lines shown in the figures are for the purpose of illustrating environment which form no part of the claimed design.
